T. C. WHITEHEAD

REFRIGERATING APPARATUS

Filed July 6, 1926

Inventor

Thomas C. Whitehead

By *Almon Hall Whitehead & Bellman*

Attorney

UNITED STATES PATENT OFFICE.

THOMAS C. WHITEHEAD, OF DETROIT, MICHIGAN.

REFRIGERATING APPARATUS.

Application filed July 6, 1926. Serial No. 120,714.

In the art of mechanical or electrical refrigeration as now extensively practiced it is necessary to employ the services of skilled engineers or mechanics to assemble and service the apparatus in use. This is particularly disadvantageous in connection with that type of electrical refrigerating apparatus which is sold without the refrigerator cabinet for installation by the purchaser in an ordinary commercial type of refrigerator, because this type of apparatus is saleable over the other types which include as a part thereof the cabinet, particularly because it may be more economically sold and is presumed to require less servicing by skilled refrigeration experts.

However, with this type of apparatus as heretofore manufactured it has been necessary in practice to employ the services of skilled mechanics for the purpose of assembling and setting up the apparatus in connection with the refrigerator and for testing and adjusting the apparatus prior to use. The need for such service increases the cost of the apparatus accordingly and is particularly burdensome to the manufacturer when the apparatus is sold in rural districts remote from the distributing branch of the manufacturer.

It is therefore one of the objects of this invention to provide a refrigerating apparatus which may be conveniently and satisfactorily manufactured and shipped in two separate units which when received by the purchaser may be readily set up and assembled in connection with the refrigerator box.

Another object of this invention consists in so constructing the apparatus and the connection between the two units thereof that the entire apparatus may be readily set up and tested at the factory whereupon the conduits connecting the two units may be sealed or closed by suitably arranged valves, to confine the refrigerant within each unit, and the conduits disconnected or uncoupled to facilitate a separate packing and shipment thereof to the purchaser. With such a construction the purchaser can mount the compressor and condenser unit exteriorly of the refrigerator box and the expansion coil unit interiorly thereof and by extending the connecting conduits of one of these units through the wall of the box and further by connecting the corresponding conduits of the two units by a valved coupling on the ends of these tubes the apparatus will be ready

for use merely by opening the valves in the tubes which places the units in communication with one another.

The above and other objects, advantages and novel details of construction of the invention will be made more apparent as this description proceeds, especially when considered in connection with the accompanying drawings wherein:

Figure 1 is a perspective view illustrative of the invention associated with a refrigerator box.

Figure 2 is a perspective view of the conduit tubes coupling element.

Figure 3 is a longitudinal sectional view through this coupling element and

Figure 4 is a sectional view therethrough taken substantially on a plane indicated by line 4—4 of Figure 3.

Referring now particularly to the drawing wherein like reference characters indicate like parts, it will be noted that there is fragmentarily illustrated a refrigerator box 10 provided with a refrigerant containing compartment 11.

The mechanical or electrical refrigerating apparatus consists of two units A and B. The unit A includes a base 12 upon which a motor 13, compressor 14 and condenser 15 are mounted. The motor 13 will drive the compressor through a belt herein indicated by the reference character 16.

The unit B includes an expansion coil 17 disposed within a brine tank 18. The reference character 19 indicates an expansion valve interposed in the tube or conduit 20 connected to the inlet end of the expansion coil 17. The reference character 21 indicates a tube connected to the outlet end of the expansion coil 17. The top loop or the upper part of the condenser 15 is connected to the discharge side of the compressor by means of a conduit 22 and the lowermost loop or part of the condenser is provided with an outlet conduit or tube 23. A tube or conduit 24 companion to the conduit 23 is connected to the inlet side of the compressor 14. Thus it will be seen that the two units A and B of the apparatus are each provided with a pair of tubes 23 and 24, and 20 and 21 respectively, which when connected will operatively associate these units.

As one convenient means for detachably connecting these two sets of tubes and for affording a valve control for the refrigerant contained in either or both of these units, I

have provided a valve coupling element 25 illustrated more particularly in Figures 2 to 4 inclusive. This coupling element consists of two, corresponding or companion parts 26 each of which is provided with a pair of longitudinally extending passages 27 for connection respectively with the conduits 20 and 21 or 23 and 24. Each of the coupling element parts 26 is provided with 10 a valve 28, herein shown as a rotary valve, provided with ports 29 adapted to be brought into or out of registration with the passages 27. Each valve will preferably be rotated through the medium of an irregular 15 shaped projection 30 on one end thereof engageable by wrench or like tool. The two parts 26 of the coupling element may be united or coupled together by means of longitudinally extending bolts 31.

20 In operation the unit A of the apparatus may conveniently be mounted or placed upon the top of the refrigerator box and the unit B will be placed within the compartment 11 and mounted or supported therein 25 in any suitable manner. Inasmuch as it is preferable that the entire surface of the tank 18 be exposed to a circulation of the air the unit B should be so positioned within the compartment 11 as to accomplish this.

30 In the illustrative embodiment of the invention as herein shown and described the tank 18 is supported spaced from the bottom of the compartment 11 by means of legs or other supports 32.

35 The units A and B may then be operatively connected by uniting the parts 26 of the coupling element 25. For accomplishing this either the tubes 23 and 24 of the unit A are passed into the box 10 through an 40 opening 33 formed in the wall thereof or the tubes 20 and 21 of the unit B may be passed outwardly through the wall of the box 10 through the opening 33. Obviously the purchaser of the apparatus may cut the 45 hole 33 through the wall of the box 10 at any desired point but as it would be less conspicuous at the rear of the box the opening 33 is shown herein as located at that point. Obviously only a relatively small 50 opening 33 need be cut into the refrigerator wall and after either set of tubes have been inserted therethrough the space around the tubes may be closed in any suitable manner.

With the units A and B mounted exteriorly and interiorly of the refrigerator as just described and with the ends of the tubes of these units connected together through the medium of the coupling element 25, the apparatus will be in condition for operation 55 merely by opening the valves 28 whereupon a free circulation is provided for the refrigerant through the entire apparatus.

The valved coupling element not only affords convenient means for readily connecting and disconnecting the conduits of the

two units but also provides means for retaining within each unit the refrigerant present therein after the testing of the apparatus at the factory. Thus the manufacturer may place in the system a sufficient amount of refrigerant and by connecting the two units as described may subject the apparatus to a thorough test to ascertain positively that the entire apparatus is free from flaws and works satisfactorily. He then may close the valves 28 in each of the coupling element parts 26 and disconnect the coupling element to permit the shipment of the units. The purchaser upon receipt of the apparatus may install the same in the manner aforescribed and by opening the valves 28 may place the units in communication with one another ready for use.

Obviously the unit A need not be mounted upon the refrigerator box but may be disposed in any other convenient place. Furthermore the unit B need not include a brine tank 18 but may consist solely of an expansion coil. Furthermore the character and arrangement of the apparatus mounted on the base 12 of the unit A may differ as found desirable or expedient. Furthermore thermostatic or other automatic control means may be associated with the apparatus for controlling the motor 13. In a like manner other types of coupling elements 25 may be utilized with equal effectiveness and the valves herein shown as associated with the companion parts of the coupling element may obviously be disposed at other points in the apparatus and retain the refrigerant in the units just as effectively.

It will therefore be apparent that the principles of this invention are capable of expression in various types of apparatus and the conventional form of construction herein shown is for illustrative purposes only and should not be considered as limiting in any respect the principles of the invention. Reservation is therefore made to make such changes in the essential and all of the non-essential details of the invention as may come within the purview of the accompanying claims.

What I claim as my invention is:

1. A refrigerating apparatus formed of two separate units one of which consists of a base and a motor, compressor and condenser mounted on said base, the other unit including an expansion coil, said second unit being mounted within a refrigerator box, conduits connected to said condenser and compressor, corresponding conduits connected to said expansion coil and a valved coupling element comprising heads connected to the ends of each set of conduits, said heads being provided with passages extending longitudinally thereof and connecting with the aforesaid conduits, valves carried by said heads for closing said passages and

means for securing the said heads together.

2. A refrigerating apparatus formed of two separate units one of which consists of a base and a motor, compressor and condenser mounted on said base, the other unit including an expansion coil, said second unit being mounted within a refrigerator box, conduits connected to said condenser and compressor, corresponding conduits connect-
ed to said expansion coil and a valved coupling element comprising heads connected to the ends of each set of conduits, said heads being provided with longitudinally extending passages adapted to register with each other and for communicating with the aforesaid conduits, and means for holding said faces in abutting relation and said passages in registration with each other. 30
- 5 10 15 20 25
3. A refrigerating apparatus formed of two separate units, one of which consists of a base and a motor, compressor and condenser mounted on said base, the other unit including an expansion coil, said second unit being mounted within a refrigerator box, conduits connected to said condenser and compressor, corresponding conduits connect-
ed to said expansion coil, and a valved coupling element comprising heads connected to the ends of each set of conduits, and having flat abutting end faces, said heads being provided with longitudinally extending passages adapted to register with each other and for communicating with the aforesaid conduits, and means for holding said faces in abutting relation. 35 40 45 50 55

In testimony whereof I affix my signature.

THOMAS C. WHITEHEAD.
